UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,380,451.

Specification of Letters Patent.

Patented June 7, 1921.

Application filed May 13, 1918. Serial No. 234,347.

To all whom it may concern:

Be it known that I, RAY S. WILBUR, a citizen of the United States, residing at Lyndhurst, in the county of Bergen, State 5 of New Jersey, have invented certain new and useful Improvements in Telephone-Exchange Systems, of which the following is a full, clear, concise, and exact description.

This invention relates to telephone 10 change systems and more particularly to those in which interoffice trunk circuits are employed for completing connections between the offices.

In such systems it is desirable to provide 15 means to enable the operator at one of the offices to readily secure the attention of the operator at the other office when desired.

It is the object of this invention to provide 20 improved signaling means for systems of this character.

To attain this object in accordance with a 25 feature of the invention, a trunk circuit is provided with means, operating upon the disconnection therefrom at one office, to produce a momentary change of the electrical 30 conditions of the trunk circuit existing at the other office, thereby causing the display of a supervisory signal for recalling the attention of the operator thereat.

The nature of this invention will more 35 fully appear from the following specification and the annexed drawing in which the figure shows, diagrammatically sufficient portions of a trunk circuit and the associated link or connecting circuits to properly illustrate the invention.

In the accompanying drawing, a trunk circuit D terminates in a jack 1 at the office or switchboard A and in a jack 24 at the office or switchboard B. A link circuit C which may be of any suitable type terminating in a plug 12, is provided at switchboard A for connection with jack 1, while a link circuit E terminating in a plug 25 is furnished at switchboard B for connection with jack 24. For the sake of clearness, certain portions of the link circuits C and E have been omitted since such portions are unessential to the proper understanding of the 45 invention. A calling signal lamp 3 is associated with the trunk circuit D at switchboard A, and supervisory signal lamps 4 and 5 are associated with the link circuits C and E, respectively.

50 It is thought that the invention may be

more fully comprehended from the following description of the operation of the system.

Assuming that the operator at switchboard B desires to call the operator at 60 switchboard A, the insertion of plug 25 in jack 24 causes the operation of relay 6 over a circuit established from battery through the normal contact of relay 7, the winding of relay 6, the right hand winding of retardation coil 8, the ring contacts of jack 24 and plug 25, the windings of retardation coils 9 and 10, the tip contacts of plug 25 and jack 24, and the left-hand winding of retardation coil 8 to ground. By the closure 65 of its contact, relay 6 establishes a circuit extending from battery, through the right-hand winding of line relay 2, the right-hand contact of cutoff relay 14, the ring conductor of the trunk, the contact of relay 75 6, the winding of relay 11, the tip conductor of the trunk, the left-hand contact of relay 14, and the left-hand winding of relay 2 to ground. Relay 2 operates to cause the lighting of the calling signal lamp 3 over a 80 circuit from battery through the lamp 3 and the contact of relay 2 to ground. Relay 11 also operates, closing its contact 18 prior to the closure of contact 17. Upon the closure 85 of contact 18, a circuit is completed from battery, through contact 18 of relay 11 and the winding of relay 19 to ground. The consequent operation of relay 19 causes the operation of relay 7, over a circuit extending from battery through the contact of relay 19 and the winding of relay 7 to ground.

The opening of the normal contact of relay 7 interrupts the connection formerly existing from the source of current to the circuit previously traced and including the 95 winding of relay 6. The subsequent closure of contact 17 of relay 11 reconnects the source of current to the circuit of relay 6 through contact 17 of relay 11, and the alternate contact of relay 7. Supervisory lamp 100 5 is lighted over a circuit established from battery through the sleeve contacts of jack 24 and plug 25, the lamp 5, and the normal contact of relay 23 to ground.

Listening key 20 may now be actuated for 105 the purpose of connecting the usual operator's telephone circuit (not shown) at switchboard B with the link circuit E. Relay 23 is also operated thereby over a circuit established from battery through the 110

right-hand winding of relay 23, resistance 22 and the contact 21 of key 20 to ground, extinguishing lamp 5. A locking circuit for relay 23 is established from battery through the contact 17 of relay 11, the alternate contact of relay 7, the winding of relay 6, the right-hand winding of retardation coil 8, the ring contacts of jack 24 and plug 25, the retardation coil 9 and the left-hand winding and the alternate contact of relay 23 to ground.

In answering the call, the plug 12 is inserted in the jack 1, thereby completing a circuit from battery, through supervisory lamp 4, resistance 13, sleeve contacts of plug 12 and jack 1, and the winding of cutoff relay 14 to ground. Relay 14 operates, disconnecting the line relay 2 from the trunk conductors and thereby extinguishing the calling lamp 3. Relay 15 now operates and relay 11 is maintained in an operated condition over a circuit established from battery through the winding of relay 15, the ring contacts of plug 12 and jack 1, the contact of relay 6, the winding of relay 11, the tip contacts of jack 1 and plug 12 to ground. Supervisory lamp 4 is therefore prevented from lighting, due to the shunt path established therearound through the contact of relay 15 and the resistance 16.

By the actuation of the usual listening key 26, the operator at switchboard A may converse with the operator at switchboard B over the trunk circuit E, in the usual manner.

Should the operator at switchboard B release the listening key 20, such operator may still be recalled by the operator at switchboard A, prior to the disestablishment of the connection, by the temporary removal of plug 12 from jack 1 since the operation of relay 23 is controlled solely by the operator at switchboard A after the release of key 20. Upon the removal of the plug 12 from jack 1, the apparatus associated with the link circuit C and with the trunk circuit D at switchboard A, will return to the normal conditions and relay 11 will release during the releasing period of the cutoff relay 14 and prior to the reconnection of the line relay to the trunk conductors. In releasing, contact 17 is adapted to open prior to the opening of contact 18. The source of current is, therefore, disconnected from the circuit previously traced, including the winding of relay 6 by the opening of contact 17. Since this circuit also includes the left-hand winding of relay 23, and since the listening key 20 has been released, relay 23 is locked over this circuit and upon the removal of the source of current therefrom, it is released, causing the lighting of lamp 5 over a circuit from battery, through the sleeve contacts of jack 24 and plug 25, lamp 5 and the normal contact of relay 23 to ground.

The control of the supervisory lamp 5 is thereby transferred to the operator at switchboard B. The subsequent opening of the contact 18 of the relay 11 releases relays 19 and 7. The release of relay 7 reconnects the source of current to the circuit including relay 6 as originally traced, to again operate relay 6 and thereby repeat the series of operations accompanying the initiation of a call from switchboard B. Upon the subsequent reinsertion of the plug 12 in the jack 1, operations such as have been described in connection with the answering by the operator at switchboard A will follow. The actuation of the listening key 20 in answering the recall operates and locks relay 23, thereby extinguishing the lamp 5, as previously described and therefore preparing the link circuit E for receiving another recall upon the subsequent release of the listening key 20. It will be noted that further removals of the plug 12, from the jack 1, prior to the actuation of the listening key 20 have no effect upon the recall signal which is continuously displayed upon the first removal of the plug.

Upon the disconnection of the link circuits C and E from the trunk circuit B, all apparatus returns to the normal position shown therefor.

It will be evident from the above description that the attention of the operator at the switchboard B may be readily recalled by the continuous display of a supervisory signal thereat, upon the removal of the plug 12 from the jack 1, by the operator at the switchboard A, while the subsequent reinsertion of the plug 12 in the jack 1, restores the apparatus to the call answering condition.

What is claimed is:

1. In a telephone exchange system, a first and a second switchboard, a trunk circuit comprising two inductively coupled sections interconnecting the switchboards, a link circuit at each of the switchboards for connection with the trunk circuit, a signaling circuit associated with the second switchboard, and means operated by the disconnection of a link circuit from the trunk circuit at the first switchboard to temporarily interrupt and to thereafter reestablish the signaling circuit.
2. In a telephone exchange system, a first and a second switchboard, a trunk circuit interconnecting the switchboards, a link circuit at each switchboard for connection with the trunk circuit, a signal control relay associated with the link circuit at the first switchboard, an operating winding for the relay controlled by the operator at the first switchboard, and a locking winding for the relay controlled by the operator at the second switchboard.
3. In a telephone exchange system, a

- trunk circuit interconnecting a first and a second switchboard, a link circuit at each switchboard for connection therewith, a relay having a locking winding, a supervisory signal for the link circuit at the first switchboard, and means operative upon the disconnection of the link circuit at the second switchboard to momentarily open the locking circuit of the relay thereby operating the supervisory signal.
4. In a telephone exchange system, a trunk circuit interconnecting a first and a second switchboard, a link circuit at each switchboard for connection with the trunk circuit, a calling signal at the first switchboard, a recall signal at the second switchboard, and means operative upon the disconnection of a link circuit at the first switchboard to continuously operate the recall signal at the second switchboard and thereafter to operate the calling signal at the first switchboard.
5. In a telephone exchange system, a trunk circuit interconnecting a first and a second switchboard, a link circuit at the first switchboard, a calling signal associated therewith at the first switchboard adapted to be effaced upon the connection of the link circuit with the trunk circuit, a recall signal at the second switchboard, and means operative upon the disconnection of the link circuit from the trunk circuit at the first switchboard to operate the call and recall signals, said calling signal being effaced upon a subsequent reconnection of the link circuit with the trunk circuit, said recall signal being unaffected thereby.
6. In a telephone exchange system, a trunk circuit interconnecting a first and a second switchboard and having its terminals connected inductively, a relay bridged across the trunk circuit at the second switchboard upon the initiation of a call from the first switchboard, a source of current normally connected with the trunk circuit at the first switchboard, a first circuit controlled by the relay adapted to disconnect the source of current from the trunk circuit immediately upon the release of the relay, thereby operating the signal at the first switchboard, and a second circuit controlled by the relay adapted to subsequently reconnect the source of current to the trunk circuit.
7. In a telephone exchange system, a trunk circuit, a relay at one end of the trunk circuit adapted to successively open its contacts upon its release, a signal at the other end of the trunk circuit, and means controlled by the successive opening of the contacts of the relay to cause the continuous operation of the signal.

In witness whereof I hereunto subscribe my name this 9th day of May, A. D. 1918.

RAY S. WILBUR.
